UNITED STATES PATENT OFFICE.

JOSEPH FOSSEL, OF GRAFTON, MASSACHUSETTS.

MECHANISM FOR GRINDING FLATS IN CARDING-ENGINES.

1,169,789.

Specification of Letters Patent.

Patented Feb. 1, 1916.

Application filed November 18, 1914. Serial No. 872,740.

To all whom it may concern:

Be it known that I, JOSEPH FOSSEL, a citizen of the United States, and a resident of the town of Grafton, in the county of Worcester and Commonwealth of Massachusetts, have invented a new and useful Improvement in Mechanism for Grinding Flats in Carding-Engines, of which the following, together with the accompanying drawings, is a specification.

The objects of my invention are to provide a grinding mechanism for the revolving flats of carding-engines by which the flats will be ground accurately and uniformly; further, to render the automatic mechanism more simple in construction and reliable in operation, and also to facilitate the manipulation of the hand operated parts of the mechanism, and I accomplish these objects by means of the mechanism herein-after described and illustrated in the accompanying drawings, in which—

Figure 1 is a side elevation of a flat-grinding mechanism embodying my invention. Fig. 2 represents the inner side of one of the tracks over which the flats are moved beneath the grinding roll. Fig. 3 represents the spring actuated bolt for engaging the flats, its inclosing case being shown in section. Fig. 4 is a front elevation of the flat-grinding mechanism, shown in sectional view on the plane of the dot and dash line 4—4, Fig. 1. Fig. 5 is a top view of the ends of three adjacent flats and a spring actuated bolt arranged to periodically engage the flats, whereby the movements of the flats beneath the grinding roll are made to carry the grinding roll toward the wire face of the flat during the operation of grinding. Fig. 6 is an end view of the spring actuated bolt by which the flats are engaged, showing the cam plate by which the bolt is released from the flats.

Similar reference characters refer to similar parts in the different figures.

Referring to the drawings, the broken lines 1, 1, Figs. 1 and 4, denote a portion of the side frame of a carding machine, to which upright stands 2, 2 are attached to support the grinding mechanism. The stands 2, 2 are provided at their upper ends with arms 3, 4. Bolted to the arms 3, 4 are bars 5, 5 which form a track over which the flats 6 are moved, in the direction of the arrow 7, beneath a revolving grinding roll 8, with the wire teeth 9 of each flat uppermost

so that they will be presented to the action of the grinding roll as the flats pass beneath it. Attached to the arms 3, 4 and above the bars 5 are guide bars 10 having flanges 11 on their inner sides.

In the operation of carding, the flats are supported at their ends upon surfaces 12 which form the "working seats" of the flat. As the flats pass beneath the grinding roll, their working seats 12 are brought uppermost and held in contact with the flanges 11. As the flats are successively moved beneath the grinding roll 8, their ribs 13 are brought into contact with arms 14 and 15 attached to the inner ends of short rocking shafts 16, 16 journaled in the upright stands 2. Levers 17 are attached to the outer ends of the rocking shafts, carrying weights 18 which serve to press the arms 14 and 15 against the ribs 13 supported thereon, in order to hold the working seats 12 of the flats in contact with the flanges 11. The weights 18 are adjustable on the levers 17 in order that the upward pressure against the flats while they are being ground will be only sufficient to prevent vibration of the flat.

Journaled in the upper ends of the arms 3, 3 is a shaft 19 to which levers 20 are attached, extending toward the arms 4, beneath the axis of the grinding roll 8. Adjustably attached to the levers 20 are boxes 21 in which the shaft 22 of the grinding roll 8 is journaled. The boxes 21 are secured to the levers 20 by bolts 23 which pass through slots 24 to allow for the vertical adjustment of the boxes, which is accomplished by means of a screw threaded bolt 25 held in a screw threaded lug 26 projecting from the lever 20, having the opposite ends of the bolt 25 bearing against lugs 27 and 28 projecting from the sides of the boxes 21.

The free ends 29 of the levers 20 rest upon arms 30 carried by a rocking shaft 31 which is journaled in the upper ends of the arms 4 of the upright stands 2. Attached to one end of the rocking shaft 31 is a lever 32, with its free end 33 bearing against a stud 34 carried by a bell crank lever which is pivoted on a stud 35 and is provided with arms 36 and 37. The arm 36 carries a weight 38 by which the bell crank is rocked in one direction, and its rocking movement is limited by an adjusting screw 39 held in a lug 40 projecting from the bell crank lever. The adjusting screw 39 is arranged to strike against a bracket or stud 41 projecting from

the side of the stand 2. The spring arm carries at its free end a tubular casing 37^a inclosing a spring actuated bolt 42, capable of a rocking and sliding motion, and having its 5 inner end provided with a flange 43 adapted to rest upon the working seats 12 of the flats as they are moved beneath the grinding roll. One edge of the flange 43 is provided with a 10 downwardly extended lip 44 which engages the edge of the flat as the latter moves beneath the grinding roll, causing the movement of the flat to impart a swinging movement to the arm 37 upon its pivotal stud 35. The movement of the arm 37, as actuated by 15 the moving flats, will move the stud 35 toward the left, Fig. 1. The free end 33 of the lever 32 will follow the movement of the stud 34 by gravity, thereby rocking the shaft 31 and depressing the arms 30 on which the 20 free ends 29 of the levers 20 rest. As the supporting arms 30 are depressed, the boxes 21 will be lowered, thereby lowering the grinding roll 8 and producing a slightly beveled or inclined surface upon the wire teeth of the flat.

During the operation of grinding, the flats are moved successively beneath the grinding roll in the direction of the arrows 7 by mechanism not shown in the drawings, 30 but which is in common use in grinding mechanisms of this class and, therefore, well known. The flat while being ground engages the lip 44, causing the arm 37 and the mechanism carried thereby to be moved 35 with the flat until the lip 44 rides upon the inclined surface 45 of a plate 46 attached by a bolt 47 to the fixed framework of the machine. As the lip 44 passes over the inclined surface 45, the bolt 42 is rocked 40 against the tension of a torsional spring 48, having one end attached to the bolt 42 and the opposite end attached to the tubular casing 37^a, thereby releasing the lip 44 from its engagement with the edge of the flat. 45 The weight 38 then reverses the motion of the bell crank, swinging the arm 37 to the right, Fig. 1, until the lip 44 is engaged by the advancing edge of the next succeeding flat which is about to pass beneath the grinding roll. The reverse movement of the bell crank also carries the stud 34 to the right, Fig. 1, thereby reversing the rocking movement of the shaft 31 and, by lifting the arms 30, restoring the grinding roll to its normal 55 elevation, at which the grinding operation upon the next flat begins. As the grinding proceeds across the surface of the flat, the grinding roll will be again lowered as already described, producing a slightly beveled or inclined surface on the beveled 60 face of the flat.

The bolt 42 is capable of a sliding movement in the tubular casing 37^a against the tension of the spring 48 which, in that case, 65 acts as a compression spring between a

shoulder 49 on the bolt and the interior end wall of the tubular casing. Screwed into the end of the bolt 42 is a spindle 50 upon which is journaled a revoluble knob 51, the body portion of which is flattened on opposite sides at 52 to fit into a slot 53 extending diametrically across the end of the tubular casing 37^a. By withdrawing the knob from the slot 53 and rotating it one-quarter turn until it rests in the shallow diametrical slot 75 54, the flange 43 and lip 44 will be drawn permanently out of engagement with the moving flats. As the swinging movement of the arm 37 is discontinued by the withdrawal of the bolt 42, the grinding roll will 80 remain in its elevated position and the grinding of the flats will be discontinued.

I claim:

1. In a mechanism for grinding flats in carding machines, comprising a rotatable 85 grinding roll, and mechanism for lowering said roll comprising a weighted bell crank, a bolt carried by said bell crank having a flange adapted to rest upon the working seat of the flat, and a lip on said flange overlapping one edge of a flat, whereby said bolt is moved by the movement of the flat, and means for rocking said bolt to disengage its lip from the flat.

2. In a mechanism for grinding flats in 95 carding machines, comprising a rotatable grinding roll, journal boxes supporting said roll, and mechanism for lowering said boxes, comprising a weighted bell crank, a bolt carried by said bell crank adapted to engage 100 a flat as it moves beneath the grinding roll, a torsional spring to hold said bolt in engagement with the flat, and a stationary cam plate for rocking said bolt against the tension of said spring to release the flat.

3. In a mechanism for grinding flats of carding engines, means for lowering the grinding roll as a flat passes beneath it, comprising a bell crank, a bolt carried by said bell crank having a flange adapted to rest 110 upon the working face of a flat, a spring applied to hold said flange against the working face of the flat, a lip on said flange overlapping one edge of the flat, and means for rocking said bolt against the tension of said 115 spring to release said lip from the flat.

4. In a mechanism for grinding flats in carding engines, comprising a grinding roll and means for lowering said roll as a flat passes beneath it, comprising a bell crank, a 120 slidable rocking bolt carried by said bell crank and arranged to engage a flat as it passes beneath the grinding roll, a spiral spring inclosing said bolt and adapted by its connection with said bolt to impart both a sliding and a rocking motion to said bolt, means for rocking said bolt against the tension of said spring to disengage the bolt from the flat.

5. In a mechanism for grinding flats in 130

carding machines, a grinding roll and means for varying the position of said roll relatively to the flat as the latter is passed beneath it, comprising a bell crank, a slideable and rocking bolt carried by said bell crank and arranged to engage a flat as it passes beneath the grinding roll, a spiral spring inclosing said bolt and connected therewith to impart a rocking and a sliding

movement to said bolt, means for rocking 10 said bolt against the torsional tension of said spring, and means for holding said bolt against the longitudinal tension of said spring.

Copies of this patent may be obtained for five cents each, by addressing the "Commissioner of Patents, Washington, D. C."

It is hereby certified that in Letters Patent No. 1,169,789, granted February 1, 1916, upon the application of Joseph Fossel, of Grafton, Massachusetts, for an improvement in "Mechanism for Grinding Flats in Carding-Engines," errors appear in the printed specification requiring correction as follows: Page 1, lines 31-33 strike out the words and numerals "shown in sectional view on the plane of the dot and dash line 4—4" and insert the words and numeral *partly shown in sectional view by the removal of the arms 4*; same page, line 66, for the word "brough" read *brought*; and that the said Letters Patent should be read with these corrections therein that the same may conform to the record of the case in the Patent Office.

Signed and sealed this 22d day of February, A. D., 1916.
